UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed March 1, 1924. Serial No. 696,344.

My invention relates to railway traffic controlling apparatus, and particularly to apparatus of the type comprising train carried governing means controlled by energy received from the trackway. More particularly my invention relates to the trackway portion of such apparatus.

I will describe two forms of trackway apparatus embodying my invention, and will then point out the novel features thereof in claims.

In the accompanying drawing, Fig. 1 is a diagrammatic view showing one form of trackway apparatus embodying my invention. Fig. 2 is a view showing a modified form of the trackway apparatus shown in Fig. 1 and also embodying my invention.

Similar reference characters refer to similar parts in both views.

Referring first to Fig. 1, the reference characters 1 and 1^a designate the track rails of a stretch of railway track, over which traffic normally moves in the direction indicated by the arrow. These track rails are divided, by means of insulated joints 2, into a plurality of successive blocks, of which only one block A—C is shown in the drawing. This block A—C is divided by means of insulated joints 2 into a forward track section B—C and a rear track section A—B. Each of the sections is provided with a track transformer designated by the reference character T with a suitable exponent and having a secondary winding 3 connected across the rails adjacent the exit end of the associated section. An impedance 5 is interposed between the secondary 3 of each track transformer T and one rail 1^a of the associated section in the usual manner. A track relay here designated by the reference character R with an exponent corresponding to the location is connected across the rails adjacent the entrance end of each section.

The primary 4 of track transformer T^c is constantly supplied with alternating current from terminals D and E, of a suitable source of energy not shown in the drawing. The primary 4 of transformer T^b is supplied with alternating current over front contact 15 of track relay R^b, from terminals D and E. It follows that when block A—C is unoccupied both relays R^a and R^b are energized; when section A—B is occupied

but section B—C is unoccupied, relay R^a is de-energized but relay R^b is energized, and when section B—C is occupied relays R^b and R^a are both de-energized.

Located adjacent the entrance end of each block is a polarized line relay designated by the reference character G with an appropriate exponent. Relay G^c is omitted from the drawing for the sake of simplicity.

Located at the entrance end of each block is a trackway signal designated by the reference character S with an appropriate exponent and controlled by the associated relay G. Each signal as here shown is a three-position semaphore signal capable of displaying a proceed, a caution or a stop indication. The control of these signals forms no part of my present invention and is omitted from the drawing for the sake of simplicity. For present purposes it is sufficient to state that each signal S is so controlled by its associated relay G that when the corresponding block is occupied, the signal indicates stop; when the corresponding block is unoccupied but the block next in advance is occupied, the signal indicates caution; and when the corresponding block and the next block in advance are both unoccupied the signal indicates proceed.

Associated with signal S^c are a pole changer P^c and a circuit controller K^c, the functions of which will be described in detail hereinafter.

Relay G^a comprises two windings 11 and 12, of which winding 12 is constantly supplied with alternating current from terminals D and E. Winding 11 of this relay is supplied with alternating current of one relative polarity when signal S^c indicates caution or proceed, and with alternating current of the other relative polarity when signal S^c indicates stop, over a circuit passing from terminal D, through pole changer P^c, wire 16, front contact 17 of track relay R^b, wire 18, front contact 19 of track relay R^a, wire 20, winding 11 of relay G^a, wire 21, and pole changer P^c back to terminal E. This circuit is closed only when relays R^b and R^a are energized, under which conditions relay R^a is supplied with current of one relative polarity, which I will hereinafter term "normal relative polarity", when signal S^c indicates proceed or caution, and with alternating current of the other relative po-

larity, which I will hereinafter term "reverse relative polarity", when signal S^c indicates stop.

Means are also provided for supplying the rails in parallel of each track section with a current which I will term a "loop" current. For this purpose I provide each track section with an impedance 6 connected across the rails adjacent the entrance end 10 of the section and a similar impedance 7 connected across the rails adjacent the exit end of the section. Section B—C is further provided with a similar impedance 8 connected across the rails at an intermediate 15 point in the section. Loop current is supplied to each section from a loop transformer designated by the reference character L with an exponent corresponding to the location. Primary winding 10 of loop 20 transformer L^B is connected across wires 18 and 21, and is therefore in parallel with relay G^A . The secondary 9 of transformer L^B is connected with impedances 6 and 7 in section A—B. Section A—B is therefore 25 constantly supplied with alternating loop current as long as relay R^B is energized. It will also be clear that the relative polarity of such loop current will be the same as the relative polarity of the current supplied to relay G^A , that is, the loop current will be of normal relative polarity when signal S^c indicates proceed or caution and will be of reverse relative polarity when signal S^c indicates stop. In similar manner the primary 10 of transformer L^c is 30 connected across wires 16 and 21, and is therefore constantly supplied with alternating current of one relative polarity or the other depending on the condition of signal S^c . Section B—C is provided with one 35 local circuit which passes from secondary 9 of transformer L^c , through wire 28, circuit controller K^c operated by signal S^c , wire 27, impedance 7 in section B—C, through both 40 rails of the section in parallel to impedance 6 and wire 26 back to transformer L^c . This 45 circuit is closed only when signal S^c indicates proceed or caution. Under these circumstances therefore loop current of normal 50 relative polarity is supplied to section B—C throughout the length of the section. A second loop circuit is provided for section B—C over which current flows from secondary 55 9 of transformer L^c , through wire 28, circuit controller K^c controlled by signal S^c , wire 29, impedance 8 in section B—C, through the rails of the section in parallel to 60 impedance 6, and wire 26 back to secondary 9 of transformer L^c . This circuit is closed 65 only when signal S^c indicates stop, but under this condition the current supplied by transformer L^c is of reverse relative polarity, and loop current of reverse relative 70 polarity is therefore supplied to section B—C between impedances 6 and 8.

The trackway apparatus herein shown and described is capable of co-operation with train carried governing means so that when the train occupies a stretch of track which is supplied with track circuit current and with loop current of normal relative polarity a proceed indication is received on the train; when the train occupies a portion of track which is supplied with track circuit current and with loop current of reverse relative polarity a caution indication is received on the train; and when the train occupies a portion of track to which the supply of either track circuit current or loop current is interrupted the train receives 75 a stop indication. It follows that both the loop current and the track circuit current may be considered as train governing currents.

As shown in the drawing signal S^c indicates proceed and block A—C is unoccupied. Relays R^A and R^B are both energized and current of normal relative polarity is supplied to winding 11 of relay G^A and to the primary 10 of transformers L^B and L^c . Sections A—B and B—C are each supplied with track circuit current and with loop current of normal relative polarity throughout the lengths of the sections. If, now, a train moving in the direction of the arrow enters block A—C such train will receive a proceed indication throughout the block. The operation of the apparatus would be the same were signal S^c at caution.

I will next assume that signal S^c is at stop, as by the presence of a train in the block to the right of point C. Pole changer P^c and circuit controller K^c are reversed and current of reverse relative polarity is supplied to winding 11 of relay G^A and to the primary 10 of each of the loop transformers L^B and L^c . Loop current of reverse relative polarity is therefore supplied to the rails of section A—B throughout their length, and to the rails of section B—C between impedances 6 and 8, but no loop current is supplied to section B—C between impedances 8 and 7. If a train enters block A—C under these conditions it will receive a caution indication from point A to impedance 8 in section B—C and a stop indication from impedance 8 to point C.

In the modification illustrated in Fig. 2 the track relays R are supplied with direct current from track batteries 13 connected across the rails adjacent the exit ends of the sections. The secondary 3 of a track transformer is interposed between each track battery 13 and one rail 1^a of the associated section for supplying alternating train controlling current to the section. Primary 4 of transformer T^B is in this view constantly supplied with alternating current from terminals D and E. Relay G^A is a direct current relay and is supplied with energy from 130

a suitable source of direct current such as a battery N over a circuit similar to the circuit for relay G^a in Fig. 1. Located at point B is an auxiliary relay J connected across wires 18 and 21. This relay is responsive to reversals of the relative polarity of the current supplied thereto. The polar contacts 32 and 37 of relay J control the relative polarity of the current supplied to primary 10 of transformer L^B. The loop circuit for section A—B is the same as in Fig. 1. The primary 10 of transformer L^C is constantly supplied with alternating current from terminals D and E. One loop circuit for section B—C passes from secondary 9 of transformer L^C, through wire 40, circuit controller K^c operated by signal S^c, wire 41, impedance 6 in section B—C, through both rails of the section in parallel to impedance 7, and wire 42 back to secondary 9 of transformer L^C. This circuit is closed only when signal S^c indicates proceed or caution, under which condition section B—C is supplied with loop current of normal relative polarity throughout the length of the section. A second loop circuit is provided for section B—C over which current flows from secondary 9^a of transformer L^C, through wire 44, impedance 8 in section B—C, through both rails of the section in parallel to impedance 6, wire 41, circuit controller K^c operated by signal S^c and wire 43 back to secondary 9^a of transformer L^C. This circuit is closed only when signal S^c indicates stop under which conditions section B—C is supplied with loop current of reverse relative polarity between impedances 6 and 8. The operation of the trackway apparatus shown in Fig. 2 when a train traverses the stretch is the same as that explained in connection with Fig. 1 and will be readily understood without further explanation.

One feature of my invention is that the same two line wires extending throughout the block for the control of line relay G located at one end of the block are utilized to control the relative polarity of the loop current supplied to the block.

Although I have herein shown and describe only two forms of trackway apparatus embodying my invention, it is understood that various changes and modifica-

tions may be made therein within the scope of the appended claims without departing from the spirit and scope of my invention.

Having thus described my invention, what I claim is:

1. In combination, a forward and a rear section of railway track, traffic governing means for said rear section including a polarized relay, a track relay for said rear section, a second track relay for said forward section, a pole changer; a circuit for said polarized relay including a front contact on said first track relay, a front contact on said second track relay, said pole-changer, and a winding of said polarized relay, and a transformer for supplying loop current to said rear section and having its primary winding connected in parallel with said polarized relay and the front contact of said first track relay.

2. In combination, a forward and a rear section of railway track, traffic governing means for said rear section including a polarized relay, a track relay for said rear section, a second track relay for said forward section, a pole changer, a circuit for said polarized relay including a front contact on said first track relay, a front contact on said second track relay, said pole-changer, and a winding of said polarized relay; a transformer for supplying loop current to said rear section and having its primary winding connected in parallel with said polarized relay and the front contact of said first track relay, and a second transformer for supplying loop current to said forward section and having a primary winding connected directly across said pole changer.

3. In combination, a block of railway track comprising a forward and a rear section, traffic governing means for said block including a relay, a pole-changer controlled by traffic conditions in advance of said forward section, and a circuit controlled by said pole-changer and including three branches in multiple for supplying current to said relay and to the rails of said forward section and to the rails of said rear section respectively.

In testimony whereof I affix my signature.

RONALD A. McCANN.
